(57) CLAIM

The ornamental design for a fourteen partition golf bag insert, as shown and described.

DESCRIPTION

FIG. 1 is a perspective view of a fourteen partition golf bag insert showing my new design;

FIG. 2 is a top plan view, the bottom plan view being plain with no design;

FIG. 3 is a top plan view of an oval bag insert;

FIG. 4 is a top plan view of an alternate embodiment of a fourteen partition golf bag insert; and,

FIG. 5 is a top plan view of the embodiment of FIG. 4 in an oval pattern.

The design shown by broken lines in FIG. 2 are for illustrative purposes only and form no part of the claimed invention.

The broken line showing of environment in the drawings is for illustrative purposes only and forms no part of the claimed design.
